UNITED STATES PATENT OFFICE.

WILLIAM BORKOWICZ, OF BALTIMORE, MARYLAND, ASSIGNOR OF ONE-FOURTH TO
JOHN BORKOWICZ, OF BALTIMORE, MARYLAND.

OIL BURNER.

Application filed March 24, 1925. Serial No. 17,885.

This invention relates to improvements in oil burners, and has for its object to provide a simple, cheap and efficient burner which can be placed in an ordinary stove, if 5 desired, and conveniently operated from the outside, and to which the oil is fed by gravity.

The invention consists of the novel construction and arrangement of the parts and 10 combination of parts hereinafter more fully set forth in the following specification and pointed out in detail in the appended claim.

In the accompanying drawing,—

Figure 1 is a top plan view of my invention.

Figure 2 is a side elevation of Figure 1. Referring to the accompanying drawings, forming part of this specification, and in 15 which like reference numerals designate like parts throughout the several views thereof, 1 designates the base provided with air vents 2 in the sides thereof, and two holes 3 in 20 the top thereof provided with flanges 4 at their lower edges. Resting in each of the 25 holes 3 on the flange 4 is a removable flanged pan 5 having a piece of asbestos 6 on its inner surface and a wire gauze piece 7 resting in said hole 3 on the upper flanged edge 30 of the pan 5 leaving a space between the asbestos piece 6 and the gauze piece 7. The 35 burners 8 have their lower ends fitted in the bosses 9 and 10 of the base 1 and are connected by the pipes 11 and 12, respectively, to the oil tank 13 which may be located at any convenient point to feed the oil by gravity to the burners 8. The said pipes 11 and 12 are provided with needle valves 14 and 15 to control the flow of oil to the burners. The said burners 8 are each provided with 40 a nipple 16 through which the oil flows in

a vaporized form and throws the flame against the baffle plates 17 causing the flame to spread, thus keeping the burner heated and causing the oil to vaporize and at the same time spreading the flame out against 45 the top of the stove in which the burner is located. When the device is to be started a small quantity of oil is poured into the pan 5 on the asbestos 6 and lighted. The wire 50 gauze 7 spreads the flame under the burner just below the nipple 16 causing the oil in the burner to quickly vaporize and form a blue flame.

Having thus described my invention, what I claim is:

An oil burner comprising a raised hollow base having a number of air vents in its sides and a number of openings in its upper surface, each opening having a flange on its lower edge, a number of burners each having one end connected to the base adjacent to one of said openings and its opposite end bent over said opening and provided with a nipple, a baffle plate secured to each of said burners above said nipples, a supply tank, 60 a pipe connected to each of said burners and each having a valve therein, a supply pipe connecting said burners with the supply tank, a flanged pan fitted in each of said openings under said burners and having its 65 flanged edge resting on the flanged edge of said openings, a wire gauze piece resting on the upper flange of each of said pans, and an asbestos disk resting in each of said pans below the flange thereof and leaving a space 70 between the gauze piece and said asbestos disk.

In testimony whereof I affix my signature.

WILLIAM BORKOWICZ.
